UNITED STATES PATENT OFFICE

EDWARD F. RAYMOND, OF LOS ANGELES, CALIFORNIA, ASSIGNOR TO JOHN GRANT, OF LOS ANGELES, CALIFORNIA

EXPANSIBLE REAMER

Application filed March 3, 1928. Serial No. 258,743.

This invention has to do with expandable reamers, underreamers and similar tools of the type used in wells. A general object of the invention is to provide an expanding reamer construction wherein the expanding cutters are both positively expanded and positively contracted.

It is typical in spring actuated expanding reamers that the cutters are expanded under the action of a spring, the spring pressure tending constantly to move the cutters to expand them. Sometimes this is done by a relative longitudinal movement between the cutters or cutter carriers and a mandrel 15 having a wedging action on the carriers; and sometimes this is done by swinging or otherwise transversely moving the cutters or cutter carriers. By whatever specific means the cutters are moved outwardly that outward movement is commonly effected by a spring actuation; and contraction is thus effected by some force acting against the spring. When the tool is being moved through a well casing the expanding spring is usually constantly urging the cutters against the casing and is thus causing considerable wear both on the casing and on the cutters.

My invention provides an additional spring actuation for the expanding cutters. 30 The arrangement is such that one spring tends to contract the cutters while the other tends to expand them; and means are provided by my invention for effectively throwing one or the other of the springs out of 35 operation at certain times so that the other spring then acts solely upon the cutters. Thus in a typical embodiment of the invention there are two springs, each capable of acting upon the cutters, one tending to throw 40 the cutters to expanded position, and the other tending to move them to contracted position. In the typical embodiment hereinafter described, I have arranged these 45 springs so that the expanding action of the cutter expanding spring is stronger than the contracting action of the cutter contracting spring; with the result that when both springs are acting upon the cutters, the stronger expanding spring throws the cutters 50 to their expanded positions. But, when it

is desired to contract the cutters, the expanding spring is definitely thrown out of operation as, for instance, by disconnecting the expanding spring from the cutters. Then the contracting spring, no longer opposed by 55 the expanding spring, acts to positively contract the cutters. Thus the cutters are both positively spring expanded and spring contracted.

My invention is broadly applicable to various types of reamers and to various types of cutters and cutter movements; but in this description I have chosen as a typical embodiment the type of reamer in which the cutters swing about longitudinal axes and 60 the springs tend to swing them between their expanded and contracted positions.

With the foregoing preliminary understanding of the invention I now proceed to a detailed description of a preferred and 70 illustrative embodiment, reference for said purpose being had to the accompanying drawings, in which

Figure 1 is a longitudinal central section of my improved reamer showing the parts 75 in expanded position.

Fig. 2 is a similar view showing the parts in contracted position.

Figures 3, 4 and 5 are, respectively, cross sections on lines 3-3, 4-4 and 5-5 of 80 Figure 1.

Figures 6 and 7 are, respectively, cross sections on lines 6-6 and 7-7 of Figure 2.

Fig. 8 is a similar section showing the parts in the positions as shown immediately 85 after contraction.

Fig. 9 is an enlargement of certain parts of Fig. 1, showing the parts in expanded position as in Fig. 1.

Figures 10 and 11 are similar views showing the parts in positions corresponding to the positions of Figures 2 and 8, respectively. 90

Fig. 12 is a similar view showing the parts in another position, and showing a variation 95 in structure; and

Figures 13 and 14 are views similar to Figs. 10 and 11, showing the parts in similar positions, but showing a further modification. 100

In the drawings, I illustrate the present embodiment as having a mandrel body 10 provided with recesses 11 in which the cutters 12 are adapted to swing and also to move longitudinally. The parts 12 are here referred to as cutters, although they may be cutter carriers which carry ultimate cutting elements either in the form of sharp edges, such as herein illustrated, or in the form of rollers or other specifically formed cutters. These cutters 12 are mounted on pivot stems 13 which extend above and below the cutters and have bearings in the body, as illustrated in the various figures. The body 10 has an upper head 10a and a lower head 10b in which the pivot stems 13 are journaled and the pivot stems project both above and below the heads 10a and 10b and have pinions 14 and 14a on their upper and lower ends, which pinions are adapted to mesh with two internal toothed ring gears 15 and 16. These two ring gears are revolvable around and vertically movable on the smaller parts 10c and 10d of the mandrel, which parts 10c and 10d extend above and below the body part of the mandrel. The part 10c has at its upper end a taper-threaded pin 20 which threads tightly into a member 21 which is, in effect, a combined sub and housing member, it having a sleeve portion 21a which extends downwardly around the mandrel part 10c and surrounds the expanding spring 25 and the ring gear 15. Likewise the lower end of mandrel part 10d has a taper-threaded pin 26 which threads into member 27 which is similar to member 21, this member 27 having an upwardly projecting sleeve 28, which surrounds the mandrel part 10d and the contracting spring 30 and also the ring gear 16. The upper member 21 may be provided with the usual taper-threaded pin 31 for connection with the usual rotary drill stem, and the lower member 27 may have the usual taper-threaded box 32 for connection with a drill bit.

Expanding spring 25 has its upper end anchored at 33 in a collar 34 which is set on mandrel part 10c; while the lower end of the spring is anchored at 35 in the ring gear 15. The contraction spring 30 has its lower end anchored at 36 in collar 37 which is set on the lower mandrel part 10d, and the upper end of spring 30 is anchored at 38 in the ring gear 16. The ring gears 15 and 16 are both rotatable about the mandrel parts and may both be longitudinally slideable thereon between the positions shown in Figures 1 and 2; and the springs 25 and 30 not only have torsion action tending to rotate the ring gears, but may also both have longitudinal compression action tending to move the ring gears longitudinally. In certain aspects of action, as hereinafter explained, the upper spring 35 need not have any longitudinal action and upper ring gear

15 need not slide vertically; but for purposes of explanation I shall assume that there is longitudinal action at the top spring as well as at the bottom one. For instance, to use some illustrative figures, the upper expanding spring 25 has a torsional action on the upper ring gear 15 tending to rotate that ring gear left-handedly when looking down upon it. This direction of rotation of ring gear 15 is indicated by the arrow in Figure 3. Tending thus to rotate the ring gear 15 left-handedly, the torsion spring 25 also tends to rotate the pinions 14 and the cutters 12 left-handedly, tending to rotate the cutters from the contracted position of Figure 7 to the expanded positions of Figure 5. Spring 25 is designed and is initially set to have a torsional action of a certain predetermined strength. For purposes of a clear understanding I shall assume that the torsional action of spring 25 on the ring gear 15 is equal to about 750 pounds. The contracting spring 30 also has a torsional action upon its ring gear 16 and therefor upon the cutters; but the torsional action of spring 30 is opposite in direction to the torsional action of spring 25 and is of considerably lesser strength. Thus the torsional action of spring 30, say equal to about 250 pounds, is exerted on ring gear 16 to rotate that ring gear in a right handed direction, looking down on the ring gear, therefore tending to rotate cutters 12 in right-handed direction about their pivot stems—to rotate the cutters 12 from the expanded positions of Figure 5 to the contracted positions of Figure 7.

Thus when both springs are acting upon the cutters they will be thrown to their expanded positions, due to the superior torsional strength of the expanding spring 25; and such is the case when the parts are in the position of Figure 1. The parts are held in the longitudinal position shown in Figure 1 by the fact that the lower spring 30 has a greater longitudinal strength than the upper spring 25. Thus, for illustration, the force exerted upwardly by spring 30 upon its ring gear 16 may be equal to about 1,250 pounds while the force exerted downwardly by spring 25 upon its ring gear 15 may be equal to about 350 pounds. When ring gear 16 is moved upwardly it moves the cutter stems 13 and cutters 12 upwardly with it; and the upper ends of the cutter stems and the upper pinions 14 press upwardly against the upper ring gear 15 and move it up to the position shown in Figure 1, compressing the upper spring 25. In this position of the parts the superior torsion of the upper spring 25 throws the cutters out to their expanded positions.

Suppose now that the tool is in the well below the casing C and is in operation in the position shown in Figures 1 and 9. When

operation is finished and it is desired to withdraw the tool from the well, it is merely drawn up against the lower end of the casing. The projecting cutters 12 come into contact with the casing and, as the tool is raised, the cutters are pushed down to the relative longitudinal position shown in Figures 2 and 10, pushing the lower ring gear 16 down and compressing the lower spring 30. At the same time the upper ring gear 15 is lowered with its set of clutch teeth 40 on its lower edge engaging in corresponding clutch recesses 41 on the upper side of head 10a. When this has occurred the ring gear 15 is held from rotation under the action of spring 25 and the pinions 14 may then move on down to the position shown in Figure 2 and out of mesh with the ring gear 15. The instant they so move out of mesh with ring gear 15, then the lower spring 30 is no longer opposed in torsional action by the upper spring 25 and accordingly the lower spring 30 instantly throws the cutters 12 to their contracted positions, in which positions the cutters may move up inside the casing. Figures 2 and 10 show the parts in contracted position and with the cutters just moving up inside the lower end of casing C. As soon, however, as the cutters 12 have been moved to contracted positions so that they can pass up inside the casing C, then the longitudinal strength of lower spring 30 again comes immediately into play and moves the parts upwardly to the position shown in Figures 8 and 11. In this position the parts are again in the same longitudinal relative positions as they were in Figure 1, but their relative rotative positions have been changed, due to the fact that the cutters 12 have been swung from their expanded to their contracted positions while out of rotative connection with ring gear 15. The different relative positions of the parts as regards rotation may perhaps best be understood by particular reference to Figures 9, 10 and 11 in which the positions correspond respectively to the positions of Figures 1, 2 and 8. In Figure 9 the cutters 12 are expanded and the ring gear 15 has rotated as far as it can in a left-handed direction—in the direction of movement indicated by the arrow on the ring gear in Figure 9. In this position the cutters (see Fig. 5) have brought up against their stops and the clutch lugs 40 may also have brought up, or substantially brought up against the shoulders 41a of clutch recesses 41 of the body head 10a. When pinions 14 are lowered out of mesh with the ring gear that gear cannot rotate any further under the impulse of spring 25 and the spring is prevented from totally unwinding. Therefore the parts go to the relative positions shown in Figure 10, the cutters 12 swinging around to the contracted positions without

moving ring gear 15 rotatively from its relative position shown in Figure 9. Then when the cutter stems 13 and their pinions 14 move upwardly, but in their contracted positions, and put the pinions 14 again into mesh with the ring gear 15, the ring gear 15 is merely moved back upwardly in that same position of rotation, with the clutch lugs 40 still up against the shoulders 41a. Accordingly the cutters 12 cannot then be swung outwardly by the action of spring 25 because, although the cutters are now in rotative connection with both springs and although the upper spring 25 is the stronger torsionally, yet that spring 25 cannot rotate the upper ring gear 15 in the direction necessary to expand the cutters. Consequently the tool can now be pulled up through the casing to the top of the well with the cutters still contracted and positively held in contracted position. This is because the expanding spring 25 is, in the last described position of the device, held totally inoperative to expand the cutters.

There are several variations of structure and action which I shall now speak of. The description thus far has dealt with the upper ring gear 15 as if its clutch lugs were (as shown in the drawings) always in the notches 41, and that therefore the ring gear is limited in rotation in all its longitudinal position. If this is the case, as illustrated, then there is no need of longitudinal movement of the upper ring gear 15 and therefore no need of longitudinal action of spring 25. However, if as shown in Fig. 12, the lugs 40 are shortened so that they do not extend into the clutch recesses 41 when the ring gear is up, then that ring gear, when in the position corresponding to Fig. 11, can and will act, under the torsion of spring 25, to swing the cutters outwardly against the casing while the tool is being raised. But the spring 25 can never fully unwind, because the ring gear in its lower position is always clutched whenever pinions 14 are out of mesh with it.

On the other hand, as shown in Fig. 13 (in which the rotative position corresponds to that of Fig. 10) the ring gear 15 may have no clutching action; so that, when pinions 14 are down and cutters 12 contracted, the ring gear 15 is free to move around far enough to unwind spring 25 completely and then when the cutters and pinions 14 move back up to the position of Fig. 14 (which corresponds to that of Fig. 11) the cutters stay in their collapsed positions because spring 25 then has no torsional tension. Figs. 13 and 14 also show the ring gear 15 without any longitudinal movement, which is unnecessary in this particular form, as also in the other form first described, but which may always be provided in the general make-up of the tool so that, by mere

variation of depths of lugs 40 and recesses 41, the different types of action may be attained.

In any case, when the tool reaches the top of the well it can then be re-set for expanding operation as follows: cutters 12 are again pushed down to the lower contracted positions of Figures 2, 10 or 13. While the cutters are thus held down the ring gear 15 is either rotated back in a direction opposite to that indicated by the arrows, and the cutters then allowed to move up to their upper positions; or the cutters are, by hand, or otherwise, swung out against the action of spring 30 to their expanded positions while they are being held down and are then allowed to move up in their expanded positions, thus putting the tool back into exactly the position of Figures 1 and 9. Then manual contraction of the cutters 12 will rotate the parts to the relative positions shown in detail in Figure 12; and the tool is then ready to be put back into the casing and to expand when it passes out of the lower end of the casing. If it is desired to rotate ring gear 15 backwards to the position of Figure 12 while the cutters 12 are lowered, a suitable wrench, having a pinion head just like one of the pinions 14 may be inserted upwardly through the special wrench opening 50 provided in the head 10a and the ring gear 15 may be rotated back to the position of Figure 12 against the torsion of spring 25. Being held in the position of Figure 12 by the wrench the cutters 12 are then allowed to move up, putting pinions 14 back into mesh with gear 15, and then upon removal of the wrench the spring 25 will act to throw the parts from the position of Figure 12 to the position of Figures 1 and 9. In the modified form in which the upper spring is allowed completely to unwind (Fig. 13) the wrench is used to wind the spring up completely. In the other forms the spring only has to be re-wound by the amount that it unwinds in its cutter expanding action.

I claim:

1. In an expansive reamer, the combination of a body, a cutter mounted therein for movement of expansion and contraction, spring actuated means for expanding the cutter, a separate spring actuated means for contracting the cutter, and means for rendering one of said spring actuated means inoperative.

2. In an expansive reamer, the combination of a body, a cutter mounted therein for movement of expansion and contraction, spring actuated means for expanding the cutter, a separate spring actuated means for contracting the cutter, and means for operatively disconnecting one of said spring actuated means from the cutter.

3. In an expansive reamer, the combina-

tion of a body, a cutter mounted therein for movement of expansion and contraction, spring actuated means for expanding the cutter, a separate spring actuated means for contracting the cutter, one of said spring actuated means being stronger than the other so as to move the cutter against the action of said other, and means for operatively disconnecting the stronger of said spring actuated means from the cutter. 70

4. In an expansive reamer, the combination of a body, a cutter mounted therein for movement of expansion and contraction and also for longitudinal movement, spring actuated means for contracting the cutter, and separate spring actuated means for expanding the cutter, which said last mentioned means is operatively disconnectible from the cutter by longitudinal movement of the cutter. 75

5. In an expansive reamer, the combination of a body, a cutter mounted therein for movement of expansion and contraction and also for longitudinal movement, spring actuated means for contracting the cutter, spring actuated means for expanding the cutter, the last mentioned spring actuated means being stronger than the first mentioned means, thereby to cause expansion of the cutter when both said means are operatively connected thereto, and means whereby said means for expanding the cutter is operatively disconnected from the cutter by longitudinal movement of the cutter. 90

6. In an expansive reamer, the combination of a body, a cutter mounted therein to swing transversely about a longitudinal axis and to move longitudinally along said axis, a spring actuated means rotatively connected with the cutter and tending to swing it in one direction, another spring actuated means rotatively connected with the cutter and tending to swing it in the opposite direction, one of said means being operatively disconnectible from the cutter by longitudinal movement of the cutter. 100

7. In an expansive reamer, the combination of a body, a cutter mounted therein to swing transversely about a longitudinal axis and to move longitudinally along said axis, a spring actuated means rotatively connected with the cutter and tending to swing it in one direction, another spring actuated means rotatively connected with the cutter and tending to swing it in the opposite direction, one of said spring actuated means being stronger than the other and being operatively disconnectible from the cutter by longitudinal movement of the cutter. 115

8. In an expansive reamer, the combination of a body, a cutter mounted therein to swing horizontally about the vertical axis to and from the body for contraction and expansion and to move vertically in the body along said axis, a torsion spring in the body 120

130

above the cutter, another torsion spring in the body below the cutter, rotative connective means between each torsion spring and the cutter, said torsion springs exerting rotative force upon the cutter in opposite directions and the upper spring being stronger than the lower spring, and the upper rotative connective means being disconnectible by downward movement of the cutter in the body.

9. In an expansive reamer, the combination of a body, a cutter mounted therein to swing horizontally about the vertical axis to and from the body for contraction and expansion and to move vertically in the body along said axis, a torsion spring in the body above the cutter, another torsion spring in the body below the cutter, two gears rotatable about the vertical axis and mounted in the body one above and the other below the cutter and rotatively connected respectively to the upper and lower springs, the cutter having upper and lower pinions adapted to mesh with the upper and lower gears, the upper pinion being slidably disconnectible from the upper gear by a downward movement of the carrier.

10. In an expansive reamer, the combination of a body, a cutter mounted therein to swing horizontally about a vertical axis to and from the body for contraction and expansion and to move vertically in the body along said axis, a torsion spring in the body above the cutter, another torsion spring in the body below the cutter, two gears rotatable about the vertical axis of the body and mounted in the body one above and the other below the cutter and rotatively connected respectively to the upper and lower springs, the cutter having upper and lower pinions adapted to mesh with the upper and lower gears, the upper pinion being slightly disconnectible from the upper gear by a downward movement of the carrier, the upper spring being the stronger of the two springs and tending to swing the cutter to expanded position, the lower and weaker spring tending to swing the cutter to contracted position, the lower spring acting also to move the cutter upwardly.

11. In an expansive reamer, the combination of a body, a cutter mounted therein to swing horizontally about a vertical axis to and from the body for contraction and expansion and to move vertically in the body along said axis, a torsion spring in the body above the cutter, another torsion spring in the body below the cutter, two gears rotatable about the vertical axis of the body and mounted in the body one above and the other below the cutter and rotatively connected respectively to the upper and lower springs, the cutter having upper and lower pinions adapted to mesh with the upper and lower gears, the upper pinion being slidably

disconnectible from the upper gear by a downward movement of the carrier, said upper gear having a limited downward movement with its corresponding pinion, and means acting upon said upper gear in its lower position to limit its rotation when its corresponding pinion is disengaged.

12. In an expansive reamer, the combination of a body, a cutter mounted therein to swing horizontally about a vertical axis to and from the body for contraction and expansion and to move vertically in the body along said axis, a torsion spring in the body above the cutter, another torsion spring in the body below the cutter, two gears rotatable about the vertical axis of the body and mounted in the body one above and the other below the cutter and rotatively connected respectively to the upper and lower springs, the cutter having upper and lower pinions adapted to mesh with the upper and lower gears, the upper pinion being slidably disconnectible from the upper gear by a downward movement of the carrier, the upper spring being the stronger of the two springs and tending to swing the cutter to expanded position, the lower and weaker spring tending to swing the cutter to contractive position, the lower spring acting also to move the cutter upwardly, said upper gear having a limited downward movement with its corresponding pinion, and means acting upon said upper gear in its lower position to limit its rotation when its corresponding pinion is disengaged.

In witness that I claim the foregoing I have hereunto subscribed my name this 11th day of February, 1928.

EDWARD F. RAYMOND.
